United States Patent

Des. 238,080

Patented Dec. 16, 1975

238,080

ELECTROMECHANICAL STORAGE AND RETRIEVAL UNIT

Paul W. Porter, Phoenixville, Pa., assignor to Sperry Univac Division, Sperry Rand Corporation, Blue Bell, Pa.

Filed Mar. 13, 1974, Ser. No. 450,643

Term of patent 14 years

Int. Cl. D14—02

U.S. Cl. D26—5 C

FIG. 1

FIG. 2

FIG. 3

FIG. 1 is a front perspective view of an electromechanical storage and retrieval unit showing my new design;

FIG. 2 is a front elevational view thereof; and

FIG. 3 is a right side elevational view thereof, the opposite side being identical to the illustrated right side.

The back of the electromechanical article storage and retrieval unit is plain and unornamented.

I claim:

The ornamental design for an electromechanical storage and retrieval unit, substantially as shown and described.
